DESIGN.

J. McC. THAIN.

BOOT JACK.

No. 17,392.

Patented June 14, 1887.

UNITED STATES PATENT OFFICE.

JOHN McC. THAIN, OF NEW YORK, N. Y.

DESIGN FOR A BOOT-JACK.

SPECIFICATION forming part of Design No. 17,392, dated June 14, 1887

Application filed April 28, 1887. Serial No. 216,527. Term of patent 7 years.

To all whom it may concern:

Be it known that I, JOHN McC. THAIN, a subject of the Queen of Great Britain, residing at New York, in the county and State of New York, have invented and produced a new and original Design for Boot-Jacks, of which the following is a specification, reference being had to the accompanying drawing.

This design has for its object to provide a novel boot-jack; and it consists in the features hereinafter described and claimed, and as illustrated by the accompanying photograph.

The letter A indicates the base of the boot-jack, comprising two curved wings, B B, extending laterally in opposite directions on curved lines from a vertical arm, C, having the prongs D, constituting a crotch. The wings B are provided with ornamental curved perforations, as shown, and the base A has a heart-shaped opening, E. The arm C is supplied with a central rib, F, and the prongs D

with a ledge, G, to ornament the crotch and arm.

Having thus described my invention, what I claim is—

1. The design for a boot-jack, consisting of the base A, comprising wings B B, extending laterally in opposite directions from the vertical arm C, and the prongs D D on the arm, substantially as shown and described. 25

2. The design for a boot-jack, consisting of the base A, comprising ornamental perforated wings B B, extending laterally from the vertical arm C, and the prongs D D on the arm, substantially as shown and described. 30

In testimony whereof I have hereunto set my hand and seal in the presence of two subscribing witnesses. 35

J. McC. THAIN. [L. S.]
